UNITED STATES PATENT OFFICE.

GEORGE HALLIDAY, OF TACOMA, WASHINGTON, ASSIGNOR OF ONE-HALF TO JOSEPH E. CASE, OF SEATTLE, WASHINGTON.

DUST COLLECTOR.

Application filed April 19, 1919. Serial No. 291,331.

To all whom it may concern:

Be it known that I, GEORGE HALLIDAY, a citizen of the United States, residing at Tacoma, in the county of Pierce and State of

5 Washington, have invented a new and useful Dust Collector, of which the following is a specification.

This invention has reference to dust collectors, and its object is to separate dust from 10 the exhaust stream of air in grain cleaning and other machinery where dust-laden air is encountered.

In accordance with the invention a stream 15 of dust-laden air is directed in a curved path away from the exhaust fan of the machinery and the dust, which is thereby directed toward the outer or convex portion of the stream, is skimmed off from the main stream and is deflected into a settling chamber 20 where it is subjected to pulsations which have the effect of causing rapid and effective separation of the dust from the air, thereby not only removing the dust rapidly from the air but causing such separation to 25 be particularly efficient and thorough.

The invention will be best understood from a consideration of the following detailed description taken in connection with the accompanying drawing forming part of 30 this specification, with the understanding, however, that the invention is not confined to any strict conformity with the showing of the drawing, but may be changed and modified so long as such changes and modifications 35 mark no material departure from the salient features of the invention as expressed in the appended claims.

In the drawing there is shown, partly in elevation and partly in section, a structure 40 embodying the invention and capable of carrying out the method of separating dust from dust-laden air.

Referring to the drawing there is shown a frame 1 which may be of any suitable 45 conformation and built of upright and cross timbers, or of other construction, to support certain parts of the machine. This frame may be complete in itself or form part of a more comprehensive machine, as 50 occasion may demand, and as the structure

of the frame is susceptible of considerable variation without affecting its function, no detailed description of the frame need be given.

Mounted on the frame 1 is an exhaust fan 55 or blower 2 from which there leads a spout 3 curving upwardly to an outlet end 4, which latter may be about upright, while the end of the spout connected to the casing of the exhaust fan is about horizontal. The spout 60 includes a curved portion 5 connecting the horizontal or tangential part of the spout with the upright portion thereof. It has been found that the radius of curvature of the outer wall of the spout, indicated at 6 65 in the drawing, should be twice that of the fan discharging through it.

Where the curved portion of the spout merges into the upright portion thereof the wall 6 has an opening 7 therethrough leading into a settling chamber 8 having an upper wall 9 of semi-circular outline merging into a slanting wall 10 directed downwardly toward another, upright, wall 11, dropping from the wall 6 about midway of 75 its length, the wall 10 approaching the wall 11 at the lower end. The settling chamber has side walls 12 and these side walls in conjunction with the wall 11 and the wall 10 approaching it at the lower end form a short 80 duct 13 leading into a cylindrical casing 14 in which there is located a circular series of blades 15 mounted on a shaft 16 concentric to the cylindrical wall of the casing 14. The duct 13 is upright and the casing 14 has 85 an outlet duct 17 displaced from the duct 13 by about 90°. The casing 14 has another outlet duct 18 located beneath the duct 13 so that it is about 90° distant from the outlet 17. Leading from the outlet duct 18 is an 90 expansion 19 thereof containing two valves 20 and 21 in tandem arrangement to the flow of material from the duct 18 through the duct expansion 19, which latter has at its lower end an outlet opening 22. Each valve 95 20 and 21 is provided with an arm 23 with which there engages a cam 24 on a shaft 25, whereby, by rotating the cam 24, the valves 20 and 21 may be made to open and close in alternation, that is, when the valve 20 100

is closed the valve 21 is open and when the valve 20 is open the valve 21 is closed.

The opening 7 is provided with a valve or board 26 pivoted within the spout at the upper edge of the opening 7 and of a length in the direction of the spout to bring the lower edge of the board toward and from the lower edge of the opening 7. The board 26 tapers in thickness from the upper pivoted edge to ward the lower edge, indicated at 27, where it is quite thin. The board 26 is designed to cleave a stream of air driven by the blower 2 through the spout 3 so that that portion of the stream of air flowing through the spout along the wall 6 will be diverted through the opening 7 into the settling chamber 8 to travel along the curved surface of the wall 9. Since the purpose of the valve or board 26 is to divert or skim off a portion of the air stream flowing through the spout 3, the board or valve is termed a skimmer. The position of the board 26 with relation to the opening 7 is determined by a rod 28 connected at one end to the board and at the other end passing through the opposite side of the spout and through a guide 29 outside of the spout, the rod 28 being screw-threaded, as shown at 30, and provided with nuts 31 on opposite sides of the guide, so that the degree of opening of the valve 26 may be determined and the valve held in the adjusted position.

Leading from the center of the upper curved portion of the settling chamber 8 is a pipe 32 opening into the eye of the fan 2, such eye being indicated at 33, and the pipe is provided with a valve 34 by means of which communication between the settling chamber 8 and the fan 2 may be varied.

The rotor of the fan 2 is mounted on a shaft 35 driven by any suitable source of power and on the shaft 35 is a pulley 36 communicating by means of a belt 37 with another pulley 38 on the shaft 16. The shafts 16 and 25 are connected by a belt 39 engaging pulleys 40 and 41 on the respective shafts.

The dust-laden air drawn from the grain cleaning or other machine, is driven by the fan 2 into and through the spout 3 and the particles of dust carried by the stream of air are caused, by gravity and centrifugal force, to hug the curved wall 6, the heavier particles of dust being closer to the wall than the lighter particles. By suitably adjusting the valve or skimmer 26 as much or little of the dust-laden air, as desired, is diverted into the settling chamber 8, following the wall 9 in its curvature and finally reaching the wall 10 down which the dust will flow to the spout 13. If only the coarsest particles of dust are to be collected, the skimmer is set with but a slight opening 65 into the chamber 8. If finer dust or even

the finest dust is to be collected the skimmer is opened accordingly, the greater opening collecting the finer dust. The operator has, therefore, entire control of the kind of dust it is desired to collect.

The dust collecting chamber 8 is rendered particularly efficient because pulsations are set up in the air therein due to the presence of the casing 14 which serves the purpose of a pulsator. The blades 15 fit the casing closely thereby constituting between them a circular series of rapidly rotating pockets taking air from the settling chamber 8 into which the air is compressed by the fan 2. The air in each pocket is carried toward the outlet 18 where the pressure is relieved and the dust falls into the continuation 19 of the duct 18 always finding a closed valve 20 or 21 as the case may be. Since the valves move in alternation the dust flowing along the wall 10 by gravity and entering the pockets between the blades 15 finds escape through the passage or duct 18 onto one or the other of the valves to ultimately escape through the opening 22. The air, however, cannot escape since there is always a valve 20 or 21 in its way and so the air is in great measure still compressed when a pocket reaches the outlet 17. Each pocket on leaving the opening 17 contains air at atmospheric or less pressure while the settling chamber 8 has in it air at more than atmospheric pressure due to the air received from the exhaust fan 2 which delivers the dust-laden air into the spout 3 under superatmospheric pressure. The air in the settling chamber 8 is under superatmospheric pressure while the pulsator represented by the casing 14 is continuously presenting a series of pockets with air at or below atmospheric pressure to the lower end of the settling chamber. For this reason there is set up in the settling chamber a rapid succession of impulses which has been found, in practice, to greatly facilitate the settling action, 100 wherefore, the deposition of the dust in the air entering the settling chamber is far more rapid than occurs in settling chambers where whirling or centrifugal action alone is relied upon.

The air passing through the spout 3 has the air and dust more or less stratified, with the dust in the form of a thin and dense mass closely hugging the concavely curved wall 6. The mass of dust hugging the wall 6 is held thereagainst by centrifugal action due to the upward curvature of the spout and the speed of travel of the air. The skimmer, being in the direct line of travel of the condensed mass of dust, collects and directs the dust and separates the major portion thereof from the stream of air which is thereby cleaned to the corresponding extent. The settling chamber directs the air, which has become richer in dust than the 130

- stream first discharged into the spout 3, along the curved surface 9, causing the dust to hug such surface and finally gravitate down the wall 10 so that by the time the stream of air in the settling chamber has slowed up it is practically free from suspended dust, the separation being greatly facilitated by the pulsations established in the settling chamber by the pulsator 14.
- 5 10 The dust leaves the settling chamber by way of the passage 13 to be carried in the pockets between the blades 15 and dropped into the passage 18 from which the accumulated dust escapes through the enlargement 19 and 15 opening 22 without material loss of air or air pressure, due to the valves 20 and 21, while what air passes through the pulsator to the opening 17 is practically free from dust.
- 20 25 Where the skimmer admits air to the settling chamber there is a constant fan pressure and were it not for the pulsator this fan pressure would remain constant within the chamber 8. By alternately and rapidly opening and closing the outlet from the settling chamber the discharge of air is variable, that is, the air in the settling chamber is alternately compressed and expanded. This has been found to be a remarkably efficient device for collecting dust, is inexpensive to construct and takes but a small space, compared with other dust collectors.
- 30 35 What is claimed is:

1. A dust collector provided with a duct having an upward curve for conveying a stream of dust-laden air and changing its course to segregate the dust on the upwardly directed concave side of the duct, means for leading the segregated dust from the duct, and a downwardly directed dust-collecting chamber into and through which the segregated dust is caused to flow in a downward direction, said collector having means associated therewith at its lower end for setting up pulsations of air in the collector during the passage of dust therethrough.
  2. A dust collector provided with means for propelling dust-laden air into and through the collector, an arc-shaped duct or spout leading upwardly from one end where it is connected to the propelling means to an exit at the other end, said duct being disposed so as to tend to segregate the dust on the uprising concave side of said spout, a settling chamber for air rich in dust having communication with the concave side of the spout adjacent to the terminal part of the uprising concave portion of the spout, and means for diverting that portion of the air stream rich in dust into the settling chamber.
  3. A dust collector comprising means for propelling a stream of dust-laden air, an arc-shaped upwardly directed duct leading therefrom for causing a segregation of the
- 5 10 15 20 25 30 35 40 45 50 55 60 65 70 75 80 85 90 95 100 105 110 115 120 125 130
- dust on the uprising concave side of the duct, a settling chamber at one side of and communicating with the duct through a port or opening in the duct, the duct discharging its substantially dust-free air vertically at a point above said port, a valve or closure for the opening having that part of the valve toward the oncoming stream of air downwardly directed, and means for moving the valve into the duct to serve as a skimmer for diverting that portion of the stream of air rich in dust into the settling chamber.
4. A dust collector comprising a duct for conveying a stream of dust-laden air and having means for segregating the dust on one side of the duct, a settling chamber connected to the side of the duct on which the dust is segregated, means in the duct for directing the air rich in dust, into and through the chamber, and means associated with the settling chamber for setting up pulsations therein, whereby the settling of dust is facilitated.
5. A dust collector comprising a duct for conveying a stream of dust-laden air and having means for segregating the dust on one side of the duct, a settling chamber connected to the side of the duct on which the dust is segregated, means in the duct for directing the air rich in dust, into and through the chamber, and means associated with the settling chamber for setting up pulsations therein, whereby the settling of the dust is facilitated, said pulsation producing means comprising a casing with a rotary series of blades therein defining pockets, and said casing having an outlet in spaced relation to the point of communication with the settling chamber.
6. A dust collector comprising a duct for dust-laden air having means for segregating the dust on one side of the duct and there discharging air rich in dust, a settling chamber connected with said discharge point of the duct, said settling chamber having a curved surface along which the air, rich in dust, is directed and the chamber having a downwardly slanting wall along which the dust may gravitate, and a pulsation causing device located at a point remote from the inlet for rich air into the settling chamber and into which the dust is deposited and from which the dust is ultimately discharged.
7. A dust collector comprising a duct for dust-laden air having means for segregating the dust to one side of the duct and there discharging air rich in dust, a settling chamber connected with said discharge point of the duct, said settling chamber having a curved surface along which the air, rich in dust, is directed and the chamber having a downwardly slanting wall along which the dust may gravitate, and a pulsation causing device located at a point remote from the

entrance to the settling chamber into which the dust is deposited and from which the dust is ultimately discharged, said pulsation causing device comprising a casing with a 5 rotary series of blades therein defining pockets into which the dust flows, said casing having an outlet in spaced relation to the inlet for dust, with the outlet having a valve structure provided with means for 10 closing the casing against free escape of air while discharging the dust.

8. A dust collector comprising a settling chamber into which dust-laden air is directed and provided with an outlet for dust, 15 and means for setting up impulses in the settling chamber, comprising a casing at the outlet end of the settling chamber, a rotary series of blades in the casing, means for providing communication between the spaces 20 between the blades and the atmosphere, and an outlet for the casing with alternately operating valves, whereby dust may be discharged from the pockets between the blades without material escape of air.

25 9. A dust collector comprising a settling chamber into which dust-laden air is directed and provided with an outlet for dust, and means for setting up impulses in the settling chamber comprising a casing at the outlet end 30 of the settling chamber with a rotary series of blades in the casing and an outlet therefor with alternately operating valves, whereby dust may be discharged from the pockets without material escape of air therewith, 35 said casing having an outlet to the atmosphere between the first-named outlet of the casing and the outlet of the settling chamber, whereby air pressure within each pocket when in communication with the settling 40 chamber is reduced to atmospheric pressure before being again brought into communication with the settling chamber.

10. A dust collector comprising a settling chamber having a curved wall against which 45 dust-laden air is initially projected and a downwardly slanting wall into which the curved wall merges and down which deposited dust can flow by gravity to an outlet, a casing communicating with the outlet of the 50 settling chamber and having outlets in spaced relation to each other and to the outlet of the settling chamber, one of the outlets of the casing being located below the outlet of the settling chamber, a rotary series 55 of blades in the casing defining a corresponding series of pockets for receiving dust from the settling chamber and conveying it to the first outlet of the casing in order, and valves in the last-named outlet opening and closing 60 in alternation for discharging dust received from the pockets without permitting material escape of air.

11. A dust collector comprising a settling chamber having a curved wall against which 65 dust-laden air is initially projected and a

downwardly slanting wall into which the curved wall merges and down which deposited dust can flow by gravity to an outlet, a casing communicating with the outlet of the settling chamber and having outlets in spaced relation to each other and to the outlet of the settling chamber, one of the outlets of the casing being located below the outlet of the settling chamber, a rotary series of blades in the casing defining a corresponding series of pockets for receiving dust from the settling chamber and conveying it to the first outlet of the casing in order, and valves in the last-named outlet opening and closing in alternation for discharging dust received from the pockets without permitting material escape of air, said casing having the second one of the outlets in order of rotation of the pockets communicating with the atmosphere for reducing air under pressure 85 in the pockets to atmospheric pressure before the pockets are again brought into communication with the settling chamber.

12. In a dust collector, a settling chamber having an inlet with means for producing constant air pressure thereat, and an outlet having means for varying air pressure thereat, whereby to set up impulses of pressure within the settling chamber to facilitate the settling of the dust in the air directed into 95 the chamber.

13. In a dust collector, a rotary fan for propelling dust-laden air, a spout leading therefrom in a substantially horizontal direction and then curved upwardly, whereby the dust is segregated on the concave side of the spout, a settling chamber associated with the spout and having a port communicating with the spout at the upper end of the curved portion thereof, a valve for the opening or port located within the spout and slanting downwardly into the spout to constitute a skimmer for directing air, rich in dust, into the settling chamber, and means at the outlet of the settling chamber for causing variations in air pressure to set up pulsations in the settling chamber for facilitating the settling of the dust in the settling chamber.

14. In a dust collector, a rotary fan for propelling dust-laden air, a spout leading therefrom in a substantially horizontal direction and then curved upwardly, whereby the dust is segregated on the concave side of the spout, a settling chamber associated with the spout and having a port communicating with the spout at the upper end of the curved portion thereof, a valve for the opening or port located within the spout and slanting downwardly into the spout to constitute a skimmer for directing air, rich in dust, into the settling chamber, and means at the outlet of the settling chamber for causing variations in air pressure to set up pulsations in the settling chamber for facilitating 130

the settling of the dust in the settling chamber, said pulsation causing means comprising a casing with a rotary series of blades therein defining pockets for receiving deposited dust from the settling chamber, means for discharging the dust without allowing the air pressure to reduce, and means whereby the air pressure in the pockets is reduced to atmospheric pressure after the discharge of the dust and before the

5 pockets are again put into communication with the settling chamber.

In testimony, that I claim the foregoing as my own, I have hereto affixed my signature.
